UNITED STATES PATENT OFFICE.

WILLIAM SPALCKHAVER, OF NEW YORK, N. Y., ASSIGNOR TO ROBERT HOE,
THEODORE H. MEAD, AND CHARLES W. CARPENTER, OF SAME PLACE.

SHEET HOLDING AND STRAINING DEVICE.

SPECIFICATION forming part of Letters Patent No. 629,933, dated August 1, 1899.

Application filed December 10, 1898. Serial No. 698,864. (No model.)

To all whom it may concern:

Be it known that I, WILLIAM SPALCKHAVER, a citizen of the United States, residing at New York city, county of Kings, and State 5 of New York, have invented certain new and useful Improvements in Sheet Holding and Straining Devices, fully described and represented in the following specification and the accompanying drawings, forming a part of 10 the same.

This invention relates to improvements in holding and straining devices for sheet material, and is more particularly directed toward improvements in those devices which 15 are intended to strain to their seats and hold in position sheet-metal printing-plates—such, for instance, as those made from aluminium, zinc, and other similar material.

In holding and straining printing-plates 20 such as have been before referred to and other sheet material to their supporting-surfaces it is frequently necessary to subject certain parts of the sheets or plates to greater tension than other parts in order to cause 25 them to lie evenly and smoothly upon their supporting-surfaces. Furthermore, when such plates are mounted upon cylinders it is desirable to make the gaps in the cylinders narrow in order that as much of the surface 30 of the cylinders as possible may be covered by the plates, or rather to make the intervals between the plates as small as possible.

The objects of this invention are to produce a plate-clamping device which shall be 35 cheap to construct, which can be easily and readily manipulated, which can be adjusted to give certain parts of the plate greater tension than other parts, and which shall be of such a character that a small opening or gap 40 in the cylinder will afford sufficient space for its location and manipulation.

With these and other objects in view the invention consists in certain constructions and in certain parts, improvements, and combinations, which will be hereinafter described, 45 and fully pointed out in the claims hereunto appended.

In the accompanying drawings, which represent concrete embodiments of the invention 50 and in which like characters of reference indicate the same parts, Figure 1 indicates a

portion of a plate-carrying cylinder, partially in section, equipped with one form of the improved holding and straining devices. Fig. 2 is a section on the line 2 2 of Fig. 1 and 55 looking in the direction of the arrow in said figure. Fig. 3 is a section on the line 3 3 of Fig. 2, looking in the direction of the arrows in said figure. Fig. 4 is a detail perspective view showing the relative location of one of 60 the jaws and the abutment. Figs. 5 and 6 are respectively detail plan and sectional views of a modification of the improved holding and straining devices.

Referring to the drawings, 1 indicates a portion of an impression-cylinder carrying a sheet-metal printing-plate 2 and having the usual gap 3 for the holding and straining devices. Suitably located in the cylinder with respect to the gap 3 is a shaft 4, which is provided with suitable means for turning the same—as, for instance, a squared head 5, though any other suitable means may be employed. The shaft preferably extends from side to side of the cylinder and finds its bearings in plates 6, which are secured to the cylinder by bolts 7 or in any other suitable manner. The shaft is provided with any suitable devices for preventing its rotation, except when it is turned by a wrench applied to the 80 squared head or in any other suitable manner. The device shown for preventing it from turning is a ratchet-wheel 8, which is engaged by a pawl 9, suitably pivoted on the plate 6 and held to its duty by an ordinary 85 plate-spring 10.

The shaft 4 is preferably provided with a series of abutments which are stationary with respect thereto. These abutments are preferably in the form of collars 11, which are secured to the shaft by means of keys 12 and having projecting ribs 13.

The gripping devices, of which there are preferably a series and which may be of any suitable form, preferably consist of a series 95 of pairs of jaws, which are mounted on the shaft 4. The lower jaw 14 of the gripping devices is provided with a pair of collars 15, which may be located at each end of the jaw and which loosely embrace the shaft. These 100 jaws have downwardly-projecting portions 16, which lie in front of the ribs 13 of the abut-

ments 11, said projections being provided with threaded apertures 16', for a purpose to be hereinafter described. The collars 15 have thickened portions 17, which are also provided with threaded apertures 17.

In the preferred form of the invention the jaw which coöperates with the jaw 14 consists of a plate 18. This plate rests against the side of the jaw 14 and has an overhanging portion 18', which forms the upper jaw. The plate is provided with projecting portions 19, having suitable apertures therethrough. Located in the threaded apertures 17', before referred to, are apertured projections, which preferably take the form of threaded screw-eyes 20. The threaded screw-eyes pass through apertures 21 in the plate 18, these apertures being sufficiently large to allow the plate 18 to have a slight vertical movement.

The jaws are drawn together by means of screws 22, which pass through the aperture in the projection 19 and engage the threaded aperture in the projection 20, these screws having squared heads to enable them to be engaged by a suitable wrench introduced through the gap in the cylinder. It is apparent that by turning the screws 22 the jaw 18 will be caused to move downward with respect to the jaw 14 and that the plate 2 or other sheet of material to be held will be clamped between the jaws. Screws 23 are preferably provided for securely locking the jaws in their adjusted position, these screws passing through suitable apertures in the plate 18. These screws 23, in connection with the screw-eyes 20, also serve to guide the plate 18 in its movement.

In order to carry out the invention, means must be provided for forcing the jaws away from the abutment in front of which they are located, and these means may be of various kinds. Preferably, however, they will consist of screws 24, which pass through the jaw 45 plate 18, engage the threaded aperture 16' in the jaw 14, and bear against the rib 13 of the abutment 11. It being remembered that there are a series of clamping devices mounted on the shaft 4, the operation of the straining and holding mechanism as a whole will be obvious.

The edge of the sheet is introduced between the jaws 18 and 14. The said jaws will then be forced together by means of the screws 22, and when the plate has been securely clamped 55 the screws 23 are adjusted to hold the jaws in position. The screws 24 are then turned by any suitable means, and each pair of jaws is thus adjusted away from the stationary abutment, the loose engagement of the collars 60 15 with the shaft 4 permitting the jaws to turn about the axis of the shaft. By adjusting the screws 24 of each pair of jaws a greater or less amount the tension on the various parts of the plate can be varied as desired. 65 When the adjustment of the several jaws along the shaft has been effected, the shaft is turned by a wrench or other suitable means,

thus carrying the abutments and the jaws away from the edge of the plate-supporting surface of the cylinder and drawing the plate 70 securely to its seat on the cylinder. The other end of the plate may be held in any desired manner. It is here shown as held by means of arms 25, mounted on a shaft 26, which is parallel to the shaft 5, said shaft being kept 75 in position to hold the arm against the edge of the cylinder by any suitable means, as by a spring. (Not shown.)

In the modification illustrated in Figs. 5 and 6 the upper jaw instead of consisting of 80 a plate 18 is formed from a block or casting 27, which has an offset portion thereon engaging an offset portion on the jaw 14, the said jaw being forced down on the lower jaw by screws. In other respects this modification 85 is the same as that heretofore described and the operation is the same.

Various modifications of the construction other than those illustrated are possible. The holding-jaws and the abutments may be 90 mounted in various ways so long as the jaws can be given an adjustment with relation to the abutments and the abutments and jaws moved together away from the plate-supporting surface. Various means may also be 95 resorted to for forcing the jaws together other than those described, and in general many other modifications may be made which will suggest themselves to skilled mechanics. Furthermore, while the invention is particularly adapted for holding sheet-metal plates on cylinders it is capable of use in many other relations—as, for instance, for holding various other kinds of sheet material, such as printers' blankets, and for holding sheets of all descriptions in position on other than cylindrical surfaces—as, for instance, on flat beds. While, also, in the preferred form of the invention a series of jaws and abutments are used, a single long abutment and a single pair of jaws 100 may be used. The invention is not therefore limited to the particular form of mechanism described nor to the particular use described, but is to be regarded as embracing all modifications which fall within its spirit 115 and scope as defined in the claims hereunto appended.

What I claim is—

1. In a sheet holding and straining device, the combination with a sheet-supporting surface, of an under jaw, a plate resting against said jaw and having an overhanging portion which forms an upper jaw, and means for giving the plate a sliding movement with respect to the under jaw, whereby the two 125 jaws are forced together, substantially as described.

2. In a sheet holding and straining device, the combination with a cylindrical sheet-supporting surface having a gap therein, an under jaw located in the gap, a plate resting against the under jaw and having an overhanging portion forming an upper jaw, and means located in the gap for giving the plate 130

a sliding movement with respect to the under jaw, whereby the jaws are forced together, substantially as described.

3. In a sheet holding and straining device, 5 the combination with a cylindrical sheet-supporting surface having a gap therein, an under jaw located in the gap, a plate resting against the under jaw and having an overhanging portion forming an upper jaw, means 10 located in the gap for giving the plate a sliding movement with respect to the under jaw, and means for forcing the jaws away from the sheet-supporting surface, substantially as described.

15 4. In a sheet holding and straining device, the combination with a sheet-supporting surface, of an under jaw, a plate resting against said jaw and having an overhanging portion forming an upper jaw, a projection on each 20 of the jaws, and means engaging the projections and co-operating therewith to give the plate a sliding movement with respect to the under jaw to force the jaws together, substantially as described.

25 5. In a sheet holding and straining device, the combination with a sheet-supporting surface, of an under jaw, a plate resting against said jaw and having an overhanging portion forming an upper jaw, a projection on each 30 of the jaws, means engaging the projections and co-operating therewith to give the plate a sliding movement with respect to the under jaw to force the jaws together, and means for forcing the jaws away from the sheet-supporting surface, substantially as described.

35 6. In a sheet holding and straining device, the combination with a sheet-supporting surface, of a pair of jaws, means for forcing the jaws together to grip a sheet, an abutment, 40 means for forcing the jaws away from the abutment, means for adjusting the abutment and the jaws with respect to the supporting surface and means for holding the other edge of the plate in opposition to the movement of the jaws and abutment, substantially as described.

45 7. In a sheet holding and straining device, the combination with a sheet-supporting surface, of a series of pairs of jaws, means for forcing the jaws together to grip a sheet, a series of abutments, means for forcing the jaws away from the abutments, means for adjusting the abutments and the jaws with respect to the supporting surface and means 55 for holding the other edge of the plate in opposition to the movement of the jaws and abutments, substantially as described.

8. In a sheet holding and straining device, the combination with a pair of jaws, of means 60 for forcing the jaws together to grip the sheet, a shaft upon which the jaws are mounted, an abutment on the shaft and stationary with respect thereto, means whereby the jaws are forced away from the abutment, means where- 65 by the shaft may be rotated and means for holding the opposite edge of the plate in opposition to the movement of the jaws and

abutment produced by the rotation of the shaft, substantially as described.

9. In a sheet holding and straining device, 70 the combination with a series of pairs of jaws, of means for forcing the jaws together to grip a sheet, a shaft upon which the pairs of jaws are mounted, a series of abutments on the shaft and stationary with respect thereto, 75 means whereby the jaws are forced away from the abutments, means whereby the shaft may be rotated to adjust the abutments and the jaws, and means for holding the opposite edge of the plate in opposition to the movement of 80 the jaws and abutments produced by the rotation of the shaft, substantially as described.

10. In a sheet holding and straining device, 85 the combination with a shaft having an abutment thereon, of a jaw mounted on the shaft and having a projection which lies in front of the abutment, means carried by the projection and engaging the abutment for moving the jaw away from the abutment, a second jaw, means for forcing the two jaws together to clamp a plate, means for rotating the shaft, and means for holding the opposite edge of the plate against the movement of the jaws and abutment produced by the rotation 90 of the shaft, substantially as described. 95

11. In a sheet holding and straining device, the combination with a shaft having a series of abutments thereon, of a series of jaws mounted on the shaft and having projections which lie in front of the abutments, means 100 carried by the projections and engaging the abutments for moving the jaws away from the abutments, a second series of jaws, means for forcing the jaws together to clamp a plate, means whereby the shaft may be rotated and 105 means for holding the opposite edge of plate against the movement of the jaws and abutments produced by the rotation of the shaft, substantially as described.

12. In a sheet holding and straining device, 110 the combination with a shaft, of a collar secured thereto having a projection which forms an abutment, a jaw provided with a pair of collars which loosely surround the shaft on each side of the stationary collar, means for 115 forcing the jaw away from the abutment, a second jaw and means for forcing the two jaws together to grip the sheet, substantially as described.

13. In a sheet holding and straining device, 120 the combination with a shaft, of a series of collars secured thereto and having projections which form abutments, a series of jaws provided with a pair of collars which loosely surround the shaft on each side of the stationary collars, means for forcing the jaws away from the abutments, a second series of jaws; means for forcing the jaws together to grip the sheet, and means whereby the shaft may be rotated, substantially as described. 125 130

14. In a sheet holding and straining device, the combination with a shaft having an abutment thereon, of a jaw provided with a pair of collars which loosely embrace the shaft on

each side of the abutment, means for forcing the jaw away from the abutment, a second jaw, and screws for forcing the two jaws together to clamp a sheet, substantially as described.

15. In a sheet holding and straining device, the combination with a shaft having a series of abutments thereon, of a series of jaws provided with a pair of collars which loosely embrace the shaft on each side of the abutments, means for forcing the jaws away from the abutments, a second series of jaws, screws for forcing the jaws together to clamp a sheet, and means whereby the shaft may be rotated, substantially as described.

16. In a sheet holding and straining device, the combination with a sheet-supporting surface, of an abutment, a jaw mounted so as to be movable with respect to the abutment, means for forcing the jaw away from the abutment, a second jaw carried by the first-named jaw, projections connected to each of the jaws and means engaging such projections for forcing the jaws together, substantially as described.

17. In a sheet holding and straining device, the combination with a sheet-supporting surface, of a series of abutments, a series of jaws mounted so as to be movable with respect to the abutments, means for forcing the jaws away from the abutments, a second series of jaws carried by the first-named jaws, projections connected to the jaws of each series, means engaging such projections for forcing the jaws together, means for moving the abutments and the jaws away from the sheet-supporting surface and means for holding the other edge of the plate in opposition to the movement of the jaws and abutments, substantially as described.

18. In a sheet holding and straining device, the combination with a support, of an abutment mounted thereon, a jaw having collars embracing the support on each side of the abutment, said collars having thickened por-

tions, projections mounted on the thickened portions, a second jaw, projections on said jaw, means engaging the projection on the jaw and the projection on the collars for forcing the jaws together, and means for forcing the jaws away from the abutment, substantially as described.

19. In a sheet holding and straining device, the combination with a shaft, of a series of abutments mounted thereon, a series of jaws having collars embracing the shaft on each side of the abutments, said collars having thickened portions, projections mounted on the thickened portions, a second series of jaws, projections on said jaws, means engaging the projections on the jaws and the projection on the collars for forcing the jaws together, means for forcing the jaws away from the abutments, and means whereby the shaft may be rotated, substantially as described.

20. In a sheet holding and straining device, the combination with a shaft, of a series of abutments stationary thereon, a series of jaws having collars loosely embracing the collars on each side of the abutments, said collars having thickened portions, a second series of jaws having portions overhanging the first series of jaws, projections in the form of screw-eyes engaging the thickened portions of the collars, projections extending from each of the second series of jaws, screws passing through one set of the projections and engaging the other set for forcing the jaws together, screws for holding the jaws firmly in their adjusted position, and screws for forcing the jaws away from the abutments, and means whereby the shaft may be rotated, substantially as described.

In testimony whereof I have hereunto set my hand in the presence of two subscribing witnesses.

WILLIAM SPALCKHAVER.
